UNITED STATES PATENT OFFICE

RUDOLPH SCHEYNST, OF CHICAGO, ILLINOIS, ASSIGNOR OF ONE-HALF TO CHAS. HOLLENBACH, INC., OF CHICAGO, ILLINOIS, A CORPORATION OF ILLINOIS

COMMINUTING MACHINE

Application filed August 21, 1931. Serial No. 558,447.

This invention relates to improvements in a comminuting machine and more particularly to that type of machines of said class which are used for the production of sausage meat.

The main object of the present invention is to provide a comminuting machine wherein the cutting elements are relatively so disposed as to counteract centrifugal force applied to the material being subjected to the action of the machine and thereby promote efficiency of the same as will more fully and particularly appear from the following specification.

Other objects of the invention will be pointed out and best understood from the detailed description of the embodiment thereof illustrated in the accompanying drawings, wherein:

Fig. 1 is a side elevation, partly broken away, illustrating a machine constructed in accordance with the invention.

Fig. 2 is a fragmentary radial sectional view thereof taken on the line 2—2 of Fig. 1.

Fig. 3 is a fragmentary perspective view of the machine.

Fig. 4 is a fragmentary perspective view of one of the cutter-carrying plates of the machine, showing the cutters in place thereon.

The machine of this invention comprises an outer substantially cylindrical casing 1, closed at its ends and which is rigidly mounted upon a suitable base 2, which may be integral.

The said casing 1 is provided with a suitable feed opening at the top thereof through which the material to be comminuted is fed, the hopper 3 for said material being arranged to feed into said opening in a well-known manner.

The casing 1 comprises, preferably, the end ring plates 4 and a relatively thick substantially semi-cylindrical wall 5, of cast iron or the like, composed of sections which are secured to said end plates, each of said sections being equipped with the cutters as hereinafter described. This cast wall-portion of said casing extends from the base 2 to the hopper 3 at the left of the latter in the instance illustrated, thus leaving the balance of said casing 1 normally open. This normally open

portion of said casing is closed in part by an arcuate sheet-metal plate 5^a extending to a point spaced from the lower end of the cast wall thereof at the right of the base to provide a discharge opening for the comminuted product. 55

Each of the said sections of said cast wall is provided with a longitudinal groove of dove-tail or equivalent shape on its inner face into which the cutters 6 and spacing blocks 60 are fitted in a well-known manner, said blocks and the portions of the said cutters 6 engaged between the same, being clamped against each other by means of set-screws 7 threaded into the end plates 4. Said set-screws also permit 65 adjustment of an entire row of cutters 6 longitudinally of said casing and laterally of the cutters. The said cutters are non-rotatable about the axis of said casing.

Mounted upon the base are standards 8 carrying bearings 9 for the shaft or trunnions 10 of the rotatable drum 11 mounted concentrically of and within the casing 1. The said drum 11 is provided with longitudinal dove-tail grooves in which similarly shaped plates 12 are fitted, one of said plates 12 being shown in Fig. 4. Each of said plates 12 is provided with a dove-tail groove in which the similarly shaped inner ends of cutters 13 are received, together with spacing blocks 14 therefor 75 which maintain said cutters 13 spaced from each other a distance equal to the spacing of the cutters 6, the latter and said cutters 13 being disposed in staggered relation to each other. 80

Set-screws 15 in the end plates 16 secured to the ends of the drum 11, bear upon the outermost cutters 13 and serve to clamp all of said cutters 13 and spacing blocks 14 firmly together and likewise permit adjustment 90 of an entire row of said cutters 13 to vary their spacing from the cutters 6 within the limits of the spacing of the latter from each other.

In the instance illustrated, the drum 11 is 95 rotatable anti-clockwise. It will be noted that the cutters 6 are disposed so that the cutting edges thereof are opposed to the direction of rotation of the drum 11 and cutters 13 and extend angularly inwardly from 100

the casing 1 in the direction of rotation of the cutters 13 so as to tend to cause material brought into contact with said cutting edges of said cutters 6 to be moved toward the drum 11.

The cutters 13 are inclined oppositely to the cutters 6 and also tend to move the material toward the surface of the drum 11.

In the existing machines of this type, the 10 cutting edges of the cutter blades are either radially disposed or are curved so the cutting edges of the cutters mounted on the drum tend to move the material outwardly toward the inner wall of the casing.

15 The drum 11 is rotated at high speed and thus exerts a strong centrifugal force on the material to be comminuted and this force is also exerted by the cutters on said drum to free them of the material and, so to speak, plaster it against the opposed inner wall of the casing 1 in a thick layer into which the cutters on the drum merely cut grooves without detaching the material.

20 By the relative angular arrangement of the cutting edges of the cutters 6 and 13 herein illustrated and described, the said respective cutters tend to move the material toward the drum 11 in opposition to the said centrifugal force and thus serve to maintain 25 said material floating between the drum and casing in the path of the cutters, the relative disposition of the cutting edges of the latter being such as to effect slicing cuts of said material.

30 35 The adjustment of the cutters 6 and 13 relatively to each other serves to regulate the degree to which the material is comminuted, it being well-known in the art that by bringing the cutters 13 into closer spaced relation 40 to the cutters 6, the material will be more finely comminuted than if said spacing is greater.

45 In effecting adjustment of the cutters 13 relatively to the cutters 6, it is best to adjust alternate sets of cutters in respectively opposite directions to assure uniform comminution of the material.

50 55 The aforesaid relative disposition of the cutters 6 and 13 constitutes the essentially novel feature of the present invention and renders the machine far more efficient than other machines of the same class which are known to the applicant.

The end plates of the drum 11 disposed op-

posite the ends of the plates 12 comprise segments which are separately removable to permit any one of the plates 12 to be removed without disturbing the remainder thereof.

In practice, the degree to which the meat or other material is comminuted, may be varied to produce a very finely divided product by doubling the number of cutters 6. This is accomplished by removing all of the cutters of each row thereof, or any selected number of said rows, and the spacing blocks for said cutters, and substituting other spacing blocks of about one-half the width of those removed. The cutters 6 and said narrower spacing blocks are then replaced with the result that a pair of said cutters 6 will be alternated with the respective cutters 13 and said cutters 6 and 13 will be far more closely spaced and thus will comminute the material subjected to their action to a far greater degree than the aforementioned described arrangement.

I claim as my invention:

A comminuting machine including a casing, a drum rotatable within and disposed concentric with said casing, and sets of cutters mounted on said casing and on said drum, respectively, the cutting edges of said cutters on said drums being angularly disposed relatively to radial planes of the axis of said drum to cause the said cutting edges of the said cutters to tend to move material coming into contact therewith toward said drum, and said cutters on said drum having their cutting edges disposed angularly to radial planes of said drum in a direction to tend to move material engaged by said cutting edges during rotation of said drum toward the surrounding casing, the respective angles of disposition of the cutting edges of the respective sets of knives being at respectively different angles to the said radial planes of the drum and casing and to cause cooperation of said cutting edges to tend to move material cut thereby toward the said drum and effect draw-cuts through said material, and means for effecting lateral adjustment of said respective sets of cutters to vary the distance of the planes of travel of the cutters on the drum with respect to the planes in which the cutters on the casing are disposed.

In testimony whereof, I have hereunto set my hand this 12th day of August, 1931.

RUDOLPH SCHEYNST.
